US00D667834S

(12) **United States Design Patent**
Coffman et al.

(10) **Patent No.:** **US D667,834 S**
(45) **Date of Patent:** **** Sep. 25, 2012**

(54) **DISPLAY SCREEN OR PORTION THEREOF
WITH GRAPHICAL USER INTERFACE**

(75) Inventors: **Patrick Lee Coffman**, San Francisco, CA (US); **Brendan Langoulant**, San Francisco, CA (US); **Stephen O. Lemay**, San Francisco, CA (US); **Angela Guzman Suarez**, San Francisco, CA (US)

(73) Assignee: **Apple Inc.**, Cupertino, CA (US)

(**) Term: **14 Years**

(21) Appl. No.: **29/377,186**

(22) Filed: **Oct. 18, 2010**

(51) **LOC (9) Cl.** **14-04**

(52) **U.S. Cl.** **D14/486**

(58) **Field of Classification Search** **D14/485-95;**
D18/24-33; D19/6, 52; D20/11; D21/324-33;
715/700-867, 973-77

(57) **CLAIM**

The ornamental design for a display screen or portion thereof with graphical user interface, as shown and described.

DESCRIPTION

FIG. 1 is a front view of a display screen or portion thereof with graphical user interface; and,

FIG. 2 is a front view of a second embodiment thereof.
The broken lines showing the display screen or portion thereof and the graphic elements form no part of the claimed design.

The dot-dash lines show unclaimed boundaries which form no part of the claimed design.
